UNITED STATES PATENT OFFICE

JOHN LAWSON AND ROBERT H. LAWSON, OF PAWTUCKET, RHODE ISLAND, ASSIGNEES
TO HEMPHILL COMPANY, OF CENTRAL FALLS, RHODE ISLAND, A CORPORATION OF
MASSACHUSETTS

MECHANISM AND PROCESS FOR PRODUCING KNITTED FABRIC HAVING LAP STRIPES

Application filed February 18, 1929. Serial No. 340,822.

This application is a continuation as to common subject-matter of our co-pending application Serial No. 233,637, filed November 16, 1927, now Patent No. 1,702,608, dated Feb. 19, 1929.

This invention relates to mechanism and process for producing knitted fabrics, particularly hosiery, and more especially seamless hosiery having lengthwise stripes, customarily known as lap stripes, made by additional threads, and having two main yarns fed in a plating relation, said plating yarns being maintained under plating control at the lap stripes, and, according to the preferred embodiment of the invention herein disclosed, said plating control is maintained while floating one of the said two plating yarns at the areas where the lap stripe threads are knitted in with the other plating yarn. Other embodiments of the invention will be also particularly referred to.

In order that the principle of the invention may be readily understood, we have disclosed certain embodiments of means for practising the same.

In the drawings:

Fig. 1 is a side elevation of a seamless stocking having the lengthwise extending stripes which, for convenience of description, we shall herein refer to as reinforced or lap stripes, which are shown as composed of blocks;

Fig. 2 is a plan view, upon a greatly enlarged scale, of the inside of a portion of the fabric shown in Fig. 1, and showing one of the sets of blocks appearing as a part of a stripe in Fig. 1;

Fig. 3 is a view similar to Fig. 1, but showing relatively wide lap stripes which are lengthwise continuous instead of being in blocks;

Fig. 4 is an inside plan view, upon a greatly enlarged scale, of a transverse portion of one of the lap stripes appearing in Fig. 3;

Fig. 5 is a detail, upon an enlarged scale, of the inside of a stocking at a narrow lap stripe, wherein three yarns are interknitted to form the stripe, which may be located

wherever desired but preferably at the back median line of the stocking;

Figs. 6 and 7 are details, upon an enlarged scale, of the inside of the fabric showing two lap stripes and the lap stripe thread floated from stripe to stripe;

Fig. 8 is a front elevation of the entire mechanism of our invention;

Fig. 9 is a left hand end elevation of said mechanism;

Fig. 10 is a right hand end elevation thereof;

Fig. 10a is a detail in vertical section upon the line 10a—10a of Fig. 10;

Fig. 11 is a plan view of the mechanism shown in Fig. 8, some of the parts being in horizontal section;

Fig. 12 is a front elevation of the head of the machine shown in Fig. 8 upon an enlarged scale;

Fig. 13 is an enlarged end elevation of the said mechanism, a part thereof being in vertical section;

Fig. 14 is a view in end elevation and somewhat diagrammatic, of the means for introducing the lap threads;

Fig. 15 is a vertical section upon the line 15—15 of Fig. 14;

Fig. 15a is a horizontal section on the line 15a—15a of Fig. 15;

Fig. 16 is a plan view of the cam barrel and cam mechanism of Fig. 11 for operating upon the jacks for elevating selected needles.

Fig. 17 is an end elevation of the cam barrel mechanism shown in Fig. 16;

Fig. 18 is a detail in plan of the pawl and immediately connected parts for operating the cam barrel;

Fig. 19 is a right hand elevation of the cam barrel mechanism shown in Fig. 16;

Fig. 20 is a left hand elevation thereof;

Fig. 21 is an inside elevation thereof;

Fig. 22 is a side elevation, upon an enlarged scale, of the thread supplies for the lap stripes and the tensioning means therefor;

Fig. 23 is a plan view of the thread tension mechanism shown in Fig. 22;

Fig. 24 is a plan view of the latch ring

with the plate inside the needle circle carrying the binder and cutter for the main yarns and also showing the means for introducing the lap threads;

5 Fig. 25 is a vertical central section of the mechanism shown in Fig. 24;

Figs. 26 and 27 are two detail views, in elevation, of a part of the binder mechanism, viewed from opposite sides thereof.

10 Figs. 28 to 31 inclusive are somewhat diagrammatic front elevations representing the jacks of those needles which take a lap thread, different jack cams being represented as functioning in the different views;

15 Figs. 32 is a perspective view of a group of ten jacks whose needles take the lap thread under control of their jack cams;

Fig. 33 is a perspective view showing a construction of jacks used in making the 20 lap stripe shown in Fig. 5;

Fig. 34 is a somewhat diagrammatic view representing the taking of a lap thread and the taking of the main or plating threads;

25 Fig. 35 is a front elevation of an arrangement of jacks, and Fig. 36 is a plan of the cooperating feeding means employed when the same lap thread is knitted into each lap stripe, being floated from each lap stripe to the next.

30 In accordance with our invention, we provide improved means whereby one or more additional threads or yarns may be introduced to make longitudinal stripes placed as desired and which we herein refer to as reinforced or lap stripes. In the disclosed embodiment of the invention, we have represented the introduction of eight such additional threads, but it is to be understood that the number may be varied as desired within

35 the scope of our invention, and that the introduction of said threads, or any of them, may be interrupted at predetermined points, and particularly at the commencement of the heel and again at the commencement of the 40 toe. The said additional threads are introduced through a special feeding device preferably similar to that shown in our said

45 Patent No. 1,702,608 and to which said threads are delivered from an elevated bobbin carrier, stand or support, here shown as 50 eccentrically arranged with respect to the needle cylinder.

The regular yarns or threads (which, merely for purposes of distinction, we will refer 55 to as the main yarns) are at least two in number, and they are fed in a plating relation, and, if desired, reverse plating mechanism may be associated therewith of any suitable

60 type, as, for example, the sinker reverse plating means shown in the patents to Robert H. Lawson, Reissue No. 16,584, April 5, 1927, and No. 1,605,896, November 2, 1926, or by a needle deflection method, such as shown in our Patent No. 1,690,076, dated Oct. 30, 1928

65 and No. 1,720,649, dated July 9, 1929.

The said two main yarns are maintained under plating control at the lap stripes, and in certain of the figures of the drawings, as, for example, Figs. 2 and 4, said plating control is represented as maintained by floating one of the two main yarns at the lap stripes, the lap threads being interknitted with the other main yarn at said lap stripes whereby at the lap stripes, there are presented one main yarn and the lap thread both knitted 75 upon the needles, and the other main yarn floated at the inner face or back of the knitted-in main yarn. At desired times the plating, which is disclosed as normal plating, may be reversed, as shown in said Lawson patents, 80 so as to produce figures or patterns of any desired character between the lengthwise extending stripes produced by the said additional thread.

In the disclosed embodiment of the invention, the said two main yarns are fed in a normal plating relation, and the additional threads by which the stripes are made upon the main yarns, are received by the predetermined needles, and desirably in such a manner that at each point where the lap stripes are formed, two threads only are received by the needles and knitted or incorporated thereby into the fabric, namely, one of the two plating yarns and the said additional thread, 95 said two plating yarns being at other points both knitted upon the needles which at such points do not receive the lap threads. Said lap threads, in the preferred embodiment of our invention, are floated at the back or inside of each lap stripe, but within the scope of our invention, the same lap thread may be employed for knitting a plurality or all of the lap stripes in which case the lap thread would be floated from each lap stripe to the 100 next lap stripe in each course, as shown in Figs. 6 and 7. In such case each lap stripe may be and preferably is relatively narrow, as shown in Fig. 6, where the two lap stripes shown are each two needles in width and the 105 lap thread is floated past eight needles between said two stripes. The lap stripes may, however, be wider, as indicated in Fig. 3, and the length of the floats may also be greater.

110 In order to feed the two main yarns in a plating relation, we preferably impart a greater tension to one of the main threads than the other, and preferably we impart the greater tension to the main yarn that in normal knitting is to appear at the outer face of the fabric.

115 We may, however, in any suitable manner so feed or control one of the main yarns as to cause the other main yarn to show at the 120 surface.

The invention may be practised in any suitable type of knitting machine, but preferably we practise the same in a circular knitting machine, of the independent needle type. 125

While the invention is not restricted to the formation of hosiery, we preferably practise the same in the production of seamless hosiery, and have herein disclosed the same without limiting our invention thereto.

While the invention may be embodied in various types of circular hosiery knitting machines, we have chosen to represent the same as applied to a machine of the well known Banner type disclosed in the patent to Joshua D. Hemphill, No. 933,443, dated September 7, 1909. In this type of machine, the needle cylinder rotates while the cam remains stationary, and although the machine disclosed is for the purpose of producing hosiery, it is obviously not limited to this class of work. We will describe the invention as applied to a machine of such type without limiting us thereto excepting when expressly so stated in the claims.

Generally stated, the knitting machine includes a needle cylinder 1 mounted upon a suitable table or base 2, constituting a part of the frame of the knitting machine, and, as is customary in this type of machine, the said needle cylinder is arranged to be rotated to form the leg and the foot of the stocking and to be reciprocated to form the heel and the toe thereof. The means for effecting the rotary and reciprocating movements are substantially the same as those shown and described in the said Hemphill patent, and, being, well known, require no further description.

A plurality of yarn feeding elements is provided, as generally indicated at 3 in Fig. 11, so as to feed not only the two main yarns for plating, but so as to feed such other yarns as may be required, as, for example, the yarn for the garter top, the yarn for the heel and the toe, the high splicing yarn and the sole reinforcing yarn.

The means for introducing the said yarn, excepting the two plating yarns, are preferably the same as those used upon the Banner machine and need not be here more fully described, and means for introducing the two plating yarns may be and preferably are the same as those disclosed in our said Patent No. 1,702,608.

The machine herein disclosed is of the independent needle type and the needles are desirably latch needles, but our invention is not limited to the use of latch needles. In the disclosed machine, however, we employ a latch ring 4 equipped with suitable binder mechanism which is particularly adapted for the purpose of our invention, and which, except where specifically otherwise stated, is substantially the same as that shown in our Patent No. 1,702,608.

The entire mechanism is driven from the main drive shaft 5, shown in Figs. 8, 9 and elsewhere, said shaft having thereon the usual pulleys and also having suitable gear-

ing including the pinion 6 for driving the large gear 7, known as the "104" gear, and which is mounted upon a shaft 8. From said main drive shaft is also driven in usual manner the quadrant 8' whereby the machine is reciprocated during the knitting of the heel and toe. The machine is also provided with usual narrowing pickers, one of which is indicated at 9 in Fig. 12, and with widening pickers, one of which is indicated at 10 in said figures. These pickers are desirably those of the Banner machine and require no further description, but we may provide means substantially as disclosed in said Patent No. 1,702,608 for moving one of the narrowing pickers out of the way of the cam for lowering the needles that take the additional threads.

The needle cylinder 1 is provided with the usual needle grooves wherein are mounted latch needles. At the upper end of the needle cylinder is provided the web holder bed ring having radial grooves receiving web holders or sinkers which may be in the form shown in said patent, it being understood that if the machine be intended to knit normal plating only, the sinkers will not be contrasted among themselves as to provide for effecting reverse plating. The sinkers or web holders, however constructed, are preferably capable of radial movement in the said grooves and are reciprocated therein by suitable cams.

The pattern cam shaft is indicated at 11 in Figs. 8, 9, and elsewhere, and is located as usual in the Banner machine, and excepting as hereinafter stated it is provided with the usual cam, ratchets, pattern chain, etc., which need not be particularly referred to. The series of levers that control the yarn fingers 3 are preferably similar to those referred to in said Patent No. 1,702,608.

We will next describe the improved means for feeding the so-called lap threads to separate selected sets of needles.

Broadly considered the mechanism herein disclosed is of the same type or character as that disclosed in our Patent No. 1,702,608, in that we provide a member mounted for rotation upon a fixed axis, which axis is parallel and eccentric to the axis of the needle circle, as contradistinguished from the concentric but swinging axis of the patent to Bosch, No. 1,615,807, and we provide means to feed said member along said axis into and out of lap-thread feeding relation to the needles. The member which actually presents the lap threads to the needles is indicated at 12 in the several figures and particularly in Figs. 13, 14, 24 and 25. Viewing the machine from the front, the said member is in this embodiment of the invention at the left side of the centre of the needle circle instead of at the right side, as in said Patent No. 1,702,608. It is positioned with its centre of

rotation inside the needle circle, and the eight or other number of tubes receive the lap threads from the supply after the same are passed through certain guides and tension devices hereinafter referred to.

Inasmuch as the member 12 is positioned upon a fixed axis close to the needle circle, it is necessary to move said member upward along its axis out of the way of the needles 10 in knitting the heel and the toe, and also for transferring. We have provided improved means for accomplishing these results which broadly are disclosed in our said patent.

Referring more particularly to Figs. 9 to 15 15a, the member 12 is shown in Fig. 15 as having a stem 13 of small diameter which is adapted to be inserted a short distance into a hollow vertical shaft 14. The extreme lower end of said shaft 14 is lengthwise slotted, as 20 represented at the four points 15, so that said lower end of the shaft 14 is resilient or springy and is adapted to be bound or pinched tightly against the short shaft 13 of the member 12. To hold said member 12 with its shaft 13 25 in position, we have provided a collar 16 which is adapted to be tightened in place just beneath the shoulder 17 of the shaft 14 by a clamping screw 18 shown in Fig. 15a.

The said shaft 14 extends vertically to a 30 considerable height, as shown in Figs. 15, 14, and elsewhere, passing through a hub 19, being slotted as indicated at 20 to receive a key 21 fitting into a keyway of the hub 19, so that the hub and the shaft 14 rotate together, said shaft 14 being permissibly moved vertically to withdraw the member 12 from the immediate vicinity of the needles during knitting of the heel and toe and during transferring. The several bobbins 22 for the lap threads are mounted upon a ring 23 which is secured by screws 24 to the basal portion 25 of the hub 19. As shown upon an enlarged scale in Fig. 13, the basal portion 25 is received in a ring carrier or annular bearing 26 and a holding ring 27 is secured in position as shown by screws 28 so that said basal portion 25, shown as having a depending flange 29, is free to be rotated within said ring carrier or annular bearing. The latter, 40 as shown in Fig. 13, has secured to its underside a crescent shaped part 30 which receives screws 31 passing through arm 32 upon a hub 33 held by set screw 34 to a vertical sleeve-bearing 35 extending downward to the bed plate to which the base 36 of said sleeve is secured by screw 37.

The basal member 25 constitutes a gear 40 and is provided with teeth 38 meshing with and driven through an opening in the ring carrier 26 by a pinion 39 upon a vertical shaft 40 extending through the sleeve 35 and at its lower end having fast thereon a pinion 41 above the collar 42 thereon. Said pinion 41 meshes with and is driven by the gear 43

fastened to the gear 44 that drives the needle cylinder.

In this or in any other suitable manner the member 12 is rotated at the proper speed to present the several lap threads to the predetermined or preselected needles and the bobbins 22 carrying the lap thread supplies are rotated concentrically with said member 12.

In order automatically to move said member 12 at the time stated and in order also to permit manual elevation of said member 12, we have provided the following mechanism shown particularly in Figs. 9, 14 and 15.

The upper end of the shaft 14 for the member 12 is recessed as indicated at 45 to receive a rod 46 pinned thereto by transverse pin 47. The upper end of said rod 46 is received in a bracket 48 secured by screws 49 to another bracket 50 through which is adapted to be guided a long rod 51 extending downward through a bearing 52 in a bracket or arm 53 secured to the creel rod 54, as shown most clearly in Fig. 14. At its lower end the said rod 51 has pivoted thereto at 55 a depending lever 56 which is lengthwise slotted at its lower end, as shown at 57, and receives a pin or screw 58 carried by an arm 58' on the hub of and turning with a ratchet 59 mounted upon a shaft 60 in the framing. Said ratchet 59 is provided with a suitable number of teeth or notches 61 adapted to be engaged by a holding pawl 62 mounted at 63 upon a convenient support, and also to be engaged by a pawl 64, which, as shown most clearly in Fig. 9, is pivoted at 65 upon an arm 66 carried by the shaft 67 of the quadrant 8'. The construction and arrangement of parts are such that when the pawl 64 is moved (in a manner to be hereinafter described) into engagement with the ratchet 59, the movement of the quadrant shaft 67 will turn the pawl 59 a number of teeth depending upon the length of time the pawl 64 is held in operative relation with the said ratchet 59. The control is such that said ratchet is turned about two teeth at or just prior to the commencement of the heel and to the commencement of the toe and is turned a greater number of teeth just prior to transferring, so as to elevate the member 12 out of the way of the needles, it being evident that the turning of the ratchet 59 any arcuate distance necessarily lifts the depending lever 56 and therefore the rod 51, because the pin 58 on the ratchet is located at the top of the slot 57.

In order to move the pawl 64 into engagement with the ratchet 59, we have herein provided a rod 68 pivotally connected to the pawl 69 at its lower end and pivotally connected at its upper end at 70 to a lever 71 which itself is pivoted upon a stud 72 upon the framing and has an end 73 adapted to engage proper cams such as 74, 75, 76 upon 130

a disk 77 that is carried by the pattern cam shaft 11.

Means are provided temporarily to hold the member 12 in elevated position, the 5 means also providing for automatic release of said member 12, so that it may be restored to its position in active relation to the needles. For this purpose, the rod 51 is notched as indicated at 78 to receive a latch 10 79, shown most clearly in Fig. 11 as a lever pivoted at 80 upon an arm 81 extending from the creel rod 54. Said latch is provided with a pin 82 against which presses a plate spring 83 upon a block 84 secured to said arm 81, 15 the construction being such that the spring 83 tends to hold the latch against the slidable rod 51, so that when the notch 78 is presented to the latch, the latter enters the same and holds the rod 51 in elevated position until 20 released therefrom. In order to release the latch 79 we have herein provided the following means. Upon the bearing 52 is pivoted at 85 a bell crank lever 86 which is so positioned with respect to the latch 79 that, when 25 swung outwardly, it engages the inner side of said latch and moves the latch out from the notch 78 and permits the rod 51 to descend and so restore the member 12 to functioning relation to the needles.

30 To the lower arm of the bell crank lever is pivotally connected at 87 a vertical rod 88 which at its lower end is pivotally connected at 89 to a lever 90 pivoted upon the stud 72 and having an arm 91, the inner end 35 of which is in the path of suitable cams upon the pattern cam shaft 11. Thus, at the proper times the latch 79 is automatically released. Preferably a handle 92 is secured to the lever arm 91 to permit the latch to be released manually if desired. Obviously, in raising the 40 rod 14 and the member 12, the hub 19 and parts 23 and 93 are not raised.

45 There will next be described the means for guiding and tensioning the lap threads from their supply to the needles.

Secured to the upper end of the hub 19 is a disk or circular plate 93 over which are a leather washer 94 and nuts 95. Upon the ring 23 are carried the bobbins 22, here eight 50 in number, and each lap thread, one of which is indicated at 96, extends upwardly from its bobbin through a guide eye 97 in a casting or other suitable member 98, one being provided for each lap thread, as shown most 55 clearly in Fig. 23, they being distributed equally about the upper face of the disk 93. Each member 98 is provided with a depending hub-like portion 99 into a socket in the under face of which is secured by a screw 100 60 a rod 101 threaded at 102 into the base 93 and there secured by a nut 103. Upon a side face of the depending part 99 there is pivoted at 104 a lever 105, having in its outer end a guide eye 106. The inner end of said 65 lever 105 is connected by a delicate coil

spring 107 with a screw 108 on a collar 109 near the lower end of the rod 101.

70 Depending also from each member or casting 98 and preferably integral therewith is an arm 110 from the lower part of which extends laterally a threaded pin 111, shown most clearly in Fig. 23, and receiving a nut 112 by which the tension of a light coil spring 113 may be varied. The said spring 113 presses upon two disks 114 and 115 loosely 75 mounted upon the pin 111 and the lap thread is received between said two disks.

80 Each lap thread 96, after passing through its guide eye 97, passes through another guide eye 116 in the said member or casting 98, thence downwardly between the two tension disks 114, 115, thence upwardly through the guide eye 106 and then through or past the disk 93 and the basal member 25 to and through the tubes 13' in the member 12. In this or in any other suitable manner the lap threads are guided and tensioned from their supply to the needles.

85 There will next be described one embodiment of means for preselecting needles and presenting them to the lap threads. In our Patent No. 1,702,608 means are disclosed for elevating groups of needles to receive the lap threads. Therein a cam is provided for engaging the jacks of those needles that are to receive the lap threads, and means are provided for controlling the said cam and for lowering the needles at the proper time. It was set forth in said patent that the groups 90 of jacks pertaining respectively to the needles that were to be elevated to take the lap threads were distributed about the cylinder 100 in accordance with the desired pattern.

95 Herein we have disclosed more elaborate means for making patterns with the lap threads. For example, the lap stripes need not be of uniform width throughout but may be of different length and may be varied in width in different parts thereof, and may be broken up into blocks of small areas or short stripes, and in fact into a great variety of 105 patterns, a single one of which is shown in Fig. 1.

110 In order to accomplish this result, we have provided upon a bracket 117, shown most clearly in Fig. 11 as secured upon the bed plate, a drum or barrel indicated generally by the numeral 118 in Figs. 11, 17, and elsewhere. Said drum or barrel is adapted to be rotated upon a vertical shaft 119 secured by a nut 120 to bracket 117. At the lower end of and constituting a portion of said drum 118 is a ratchet 121, and above and concentric therewith are the desired number of pattern disks, here shown as three in number, namely, 122, 123, 124. They are respectively provided with cams and spaces which will be more fully described in connection with the particular fabric represented in 125 Figs. 1 and 2.

In order to rotate the said drum 118 in a step by step manner, there is provided beneath the ratchet 121 a pivoted pawl carrier 125 concentric with said ratchet and having secured to its upper surface a pivoted pawl 126 to engage and turn said ratchet 121. Said pawl carrier 125 is operated automatically at the desired times in the following manner.

Referring particularly to Fig. 10, the "104" gear 7 is provided with two cams 127, 128, secured thereon with capacity for accurate adjustment. In the rotation of said gear the cams ride under and elevate a rod or pin 129 vertically mounted in a sleeve 130 provided in the bed plate. Upon the upper end of the rod or pin 129 is a nut 131 which, when the rod is moved upward by one of the cams 127 or 128, engages and rocks a short arm 132 pivoted at 133 upon a short shaft carried by a bracket 134 upon the bed plate. As shown most clearly in Figs. 10 and 11, there is fast upon said short shaft 133 an arm 135 which has pivoted thereto at 136 a long horizontally extending link 137 connected at 138 to a bell crank lever 139 pivoted at 140 upon the bed plate. Connected to the other arm of the bell crank lever at 141 is another horizontal link or rod 142 which, as shown in Figs. 16 and 18, is pivotally connected at 143 to the pawl carrier 125.

Thus in each rotation of the 104 gear, two impulses are imparted to the pawl 126 and the ratchet 121 of the drum 118.

Referring now to certain of the patterns herein represented as merely typical of variations in the lap stripes or figures, and referring first to Figs. 1 and 2 and the drum controlling means therefor shown in Fig. 17, there is represented in Fig. 1 a hose or stocking 144 of a seamless character showing three of its lap stripes at 145, 146, 147. Obviously the lap stripes may be of colors contrasting among themselves to the desired extent, and contrasting if desired in material with the body yarn or yarns, and also if desired among themselves.

Referring to any one of the lap stripes, it will be observed that in the particular pattern represented each stripe is made up of a series of what may be called small blocks or areas, one of which is represented on a greatly enlarged scale in Fig. 2. Each of said blocks or areas is shown as ten needle wales in width in extreme measure, and each lap thread is taken by preselected needles, so that certain needles in the making of each block or area receive the lap thread and certain of them do not.

In Fig. 2, for convenience of description, ten of the wales are marked *a, b, c, d, e, f, g, h, i, j*. The block or area in Fig. 2 may be regarded as made up of three different parts under the control respectively of the cams 124, 123, 122, said three parts appearing twice, once in reverse order, so as to make in

effect a block or area which surrounds a cross made only of both of the body yarns. The first of said parts appears in the wales *e, f*, at both the upper and lower portions of the figures. The second of said parts appears in the wales *c, d, g, h*, and the third of said parts appears in the wales *a, b, i, j*. Viewing each of said wales at the said parts, it is to be understood that what may be termed the body plating thread A is knitted upon all the needles of the needle circle including the wales wherein said parts are formed. The other plating yarn B, it will be observed, is knitted in the stocking or other fabric under suitable plating control upon all the needles excepting those needles which are making the lap stripe. At said needles the said plating yarn B is floated as indicated at B' in Fig. 2. The lap thread which is indicated at C is knitted into the lap stripe, and to make the said first part is knitted into the wales *e, f*, and is itself floated at the back of the lap stripe, as indicated at C'. This procedure is carried out to make the several parts of the block, as shown in the wales *a* to *j*, and it will be observed that in the wider parts of the block the floated part of each lap thread is longer. In the hollow cross which is surrounded by the block, the two body threads A, B are knitted together in a plating relation. The plating thread B, as already stated, is not knitted into the block in those parts of the wales thereof where the lap thread C is knitted in. In other words, in this construction shown in Figs. 1 and 2, the lap stripe is not composed of three yarns all knitted upon the same needles as in our said Patent No. 1,702,608, only one of the body yarns and the lap thread being knitted upon the same needles, and at the within cross-areas or in the same wales where the lap thread is not knitted in, both the body yarns are knitted in in plating relation.

The two yarns A, B are maintained under plating control at all times and the short floating of one of said body yarns is an incident to the maintenance of plating control at all times, as broadly claimed in our said patent.

Referring to Fig. 17, the disk 122 is provided with four cams, two of which are shown at 148, there being a space 149 between the two cams represented. The disk 123 is provided with eight cams 150 and between the adjacent cams are spaces 151. The disk 124 has four cams 152 and between adjacent cams are spaces 153. In a manner to be herein-after described, the said cams control certain jack cams which are moved into and out of functioning relation to the jacks of the desired needles, whereby the proper needles are preselected and are presented in accordance with such preselection to take the lap threads in the proper number of courses.

We will next describe the means whereby

the cams upon the barrel 118 control the selection and presentation of those needles that are to take lap threads.

Referring principally to Figs. 16, 17, 19 to 5 21 and 28 to 33, the three disks 122, 123, 124, act respectively upon levers 154, 155, 156 pivoted at 157 in a bracket 158. In a guide way 159 adjacent to said bracket are mounted the sliding stems 160, 161, 162 of three jack 10 selecting cams 163, 164, 165, which are mounted in superposed spaced relation to each other, as clearly shown in Figs. 21, 28, 15 29, 30, etc. The ends of the levers 154, 155, 156 engage sockets respectively in the said slides 160, 161, 162, and according to the dictates of the cams upon the disks 122, 123, 124 move said jack cams inwardly so as to come in the path of certain butts upon the needle 20 jacks, as will be described. Attached to each of the several cams 160, 161, 162, by bars, one of which is shown at 166, are three jack depressing cams numbered respectively 167, 168, 169.

All of the needles are provided with jacks, 25 such as 170, positioned respectively beneath them in their grooves, being independent of the needles, as clearly appears from Figs. 28 to 33. One half the circle of jacks (namely, those at the heel side of the stocking) is provided with short butts 171, with the exception of two jacks 172 in Fig. 33, which, in the present embodiment of the invention, are positioned at the median back line of the hose or stocking. The remaining half of the jacks 30 (namely, the instep jacks) has at the lower ends long butts of the same length as the two jacks 172. In addition to the said long and short butts, which are at the lower ends of the jacks, those jacks, wherever situated, whose 35 needles are to participate in the knitting of the lap threads are provided with other butts arranged at different heights. Herein four such other butts are provided at different heights, only two other such additional butts 40 being upon any one needle jack. For example, in Fig. 32, we have represented a group of jacks 173 which are employed in making the block shown in Fig. 2. In said Fig. 32, are represented ten jacks which correspond to the needles knitting the ten needle wales *a* to *j* of Fig. 2. Upon each of said 45 ten jacks there is an upper butt 174; upon the first two and the last two are the somewhat lower butts 175; upon the third and fourth 50 and seventh and eighth are the still lower butts 176; and upon the fifth and sixth jacks are the still lower butts 177. The heights of the jacks 175, 176, 177 correspond to the levels of the elevating jack cams 163, 164, 165. 55 Viewing Fig. 12, it will be understood that whatever jacks are elevated by the respective jack cams 163, 164, 165, are engaged by a cam 178 secured to a bracket 179 upon the knitting cam plate 180, the needles themselves being lowered by the instep cam 181.

The said cam 178, as indicated most clearly in Fig. 28, through its action in engaging the upper butts 174 depresses the jacks slightly so that their butts 175, 176 or 177, as the case may be, engage the under side of the jack depressing cams 167, 168, 169, this occurring after the corresponding needles have taken the proper lap threads. Those needles which do not take a lap thread travel with their butts 171 at a level indicated by the line 182 in Fig. 13, having previously been brought with all the needles to such level by a cam 182' positioned beyond the knitting cams. All the needles whose butts are at the level 182 ride up the upper face of a cam 183 supported in a housing 184 upon the bed plate 2, whereby those needles will take a main body yarn A as well as yarn B, Figs. 2 and 34. The said cam 183 is provided with this purpose in view, because during patterning work the knitting cam 185 has been moved automatically slightly outward as hereinbefore referred to. Those needles which do take the lap thread have their butts at the low level indicated at 186 in Fig. 12, having been moved down to that level by the respective cams 167, 168, 169, and hence their butts pass below the cam 183 and accordingly they take only the main thread A and permit the main thread B to float as indicated at B' in Fig. 2. Viewing Fig. 34, it will be observed that four needles indicated at *a'*, *b'*, *i'*, *j'*, were elevated to take a lap thread from the member 12, said needles being those which knit the lap thread into the wales *a'*, *b'*, *i'*, *j'* of Fig. 2. Thereafter the needles function as already described and take one or both of the main or plating yarns A, B, as already described. Said plating yarns A, B, are fed in a plating relation, the yarn B having preferably the greater tension imparted thereto, and plating control of said yarns is maintained at all times, including the times when the plating yarn B is floated at B'. 95

In addition to the three cams 163, 164, 165 there is supported in the housing 159 a fourth and lowermost cam 187 shown most clearly in Fig. 20. All of said four cams are normally retracted by light springs 188 connected thereto and to a suitable support. Said lowermost cam 187 is not subject to the control of the cams upon the disks 122, 123, 124, but is adjusted to position by the screw 189 and is adapted to engage only the two long butts 172 of the jacks shown in Fig. 33, the purpose whereof, as already stated, is to effect the knitting in of a lap thread at the median back line of the stocking. 100

As shown most clearly in Figs. 9 and 19, there is provided a vertical rod 190 suitably guided and having near its lower end a roll 191 to engage a suitable cam upon one of the disks or drums on the pattern cam shaft 11. Said rod 190 is guided at its lower end by a pin 192 received in the vertical slot 193. 125

At its upper end, as shown in Fig. 9, said 130

rod 190 is stepped to provide three levels 194, 195, 196, and those levels are adapted to engage an arm 197 on a lever 197' (Fig. 21) that in turn acts upon the respective levers 154, 155, 156, and a lever 198 (Fig. 17) for the cam 187, whereby all of said cams remain fully inward or are moved outward into either of two positions, according to the shoulder which functions.

- 10 It is to be understood that while in Fig. 32 we have represented the butts 174, 175, 176, 177 as long, said butts are long under the long butt needles and short under the short butt needles; that is to say, the jacks under the 15 needles which knit the back half of the hose or stocking and the sole are provided with short butts 174 to 177, if such needles are to receive lap threads, and those needles which are to receive lap threads at the front of the 20 leg of the stocking or at the top of the foot are provided with long butts at the corresponding levels. When the shoulder 196 functions, the cams 163, 164, 165, 187 are all the way in, and therefore act upon the long 25 butt and the short butt jacks, and hence, according to the disclosed arrangement, down to the beginning of the heel.

The lap threads are, according to the present disclosure, intended to be knitted into the 30 top of the foot but not into the sole thereof. Accordingly the level 195 moves the said cams 163, 164, 165 and 187 to an intermediate position, so that the short butt needles (namely, the needles which make the heel 35 and toe) do not receive lap threads. When the level 194 acts, the said cams 163, 164, 165, 187 are moved all the way out and no lap threads are knitted in. This would be the condition when knitting the heel and the toe.

- 40 In Figs. 28, 29 and 30 we have represented respectively the cams 163, 164 and 165 as moved into functioning position and hence causing the elevation of the jacks whose butts are provided at the corresponding levels of 45 said cams, namely, the butts 175, the butts 176 and the butts 177.

In Fig. 3, we have represented at 199 a hose or stocking having lap stripes 200 each of uniform width throughout. Said lap stripes 50 are knitted in the manner already described with respect to Figs. 1 and 2, and the needle jacks are so provided with butts as in each course to cause the elevation of all the needles 55 which receive and knit the lap threads, ten such needle wales being indicated in Fig. 4 within the bracket 200. In such fabric, one of the plating threads is indicated at A, as heretofore, the other being indicated at B, as 60 heretofore. The lap thread is indicated at C and in those wales where the lap thread is knitted in, the plating yarn B is floated as indicated at B'. In other words, the principle of operation in making the lap stripes of 65 Figs. 3 and 4 is the same as that employed

in making the lap stripes of Figs. 1 and 2, but the patterning effect is more simple.

In Fig. 5 is represented the stripe which is made by the action of the jacks shown as having long butts 172 in Fig. 33. Preferably the lap stripe as indicated at 201 is knitted at the back median line of the hose or stocking, and in this case only the two plating yarns and the lap thread are all knitted in upon two needles in the identical manner disclosed in our Patent No. 1,702,608. During the knitting of said lap stripe which may be of any desired width, the two plating yarns are maintained under plating control.

We have provided means whereby the lap 80 stripes, wherever they appear, and whether they be of a simple form or not, are all knitted with the same identical lap thread. Such construction of stripes is shown in Figs. 6 and 7. In Fig. 6, the lap thread is indicated 85 at 202, and it is there shown as being knitted into two groups of two wales 203, 204, spaced apart by a number of wales between which the lap thread is floated, as indicated at 205. In Fig. 7, the same construction of fabric is 90 shown excepting that the lap thread 202 is represented as knitted into two groups of three wales 206, 207 and floated therebetween. Such floating is continued from stripe to stripe throughout the extent of the 95 stocking or other fabric.

In order to make the lap stripes in this manner, we may employ any suitable mechanism, for example, that shown in Figs. 35 and 36. In Fig. 35, we have represented an 100 arrangement of jacks for knitting the lap stripes each three needles in width, as represented in Fig. 7. In said Fig. 35, we have represented three groups 208, 209, 210, of jacks for elevating the needles, said jacks 105 having only butts 211 at their lower ends, said butts being long under long butt needles and short under short butt needles. Said jacks are elevated by a cam 187' which functions like the cam 187 already described. The 110 lap thread is shown at 202 in Fig. 36, and it is introduced through a single eye 213 of a member 212 corresponding to the member 12 of the main construction, and substantially similarly supported except that it is stationarily 115 mounted and not rotatable about its axis. Said member is, however, moved along its axis in the manner described with respect to the member 12 in order to move the same out of functioning relation to the needles 120 during heel and toe work and during transferring. It is unnecessary further to illustrate the means for supporting said member 213, which is provided with a single guide eye only, as but a single lap thread is supplied by the member 213, being knitted onto groups of three needles each and floated between the groups.

In Figs. 24 to 27 we have represented improved means for keeping the lap threads out 130

of the binder and the cutter, means for this purpose being first disclosed in our said Patent No. 1,702,608.

In said figures, the plate within the needle circle is represented at 214. It is cut away as indicated at 215 to provide an elongated, tapering, crescent-shaped finger 216 extending about substantially one half the circumference of the needle circle at the inside of such circle. The lap threads indicated at C, in the rotation of the needle cylinder in the direction of the arrow, ride along the upper surface of said finger 216, extending from the needles to the fabric and as they successively slide off the end 217 of said finger, the tensions for the lap threads take up the slack, said tension acting constantly for this purpose. When the lap threads pass off the point 217 of the finger 216, they pass under the solid portion of the plate 214 and hence cannot get into the binder and cutter, which may be of any suitable construction.

Herein for the purpose we have represented a bracket 218 extending from the usual support and associated therewith and with the plate 214 are the binder 219 and the cutter 220 which are adapted to be operated in usual manner by an arm 221 which herein is in part of U shape so as to co-act with both binder and the cutter. Said arm 221 has pivoted thereto a link 222 for operating the binder and a link 223 for operating the cutter. Preferably we provide a guide 224 secured fixedly at 225 to the plate 214 and having its inner end bent up, as indicated in Fig. 26, to insure the lap threads passing thereunder.

Having thus described certain embodiments of means and the best method known to us for practising our invention, it is to be understood that although specific terms are employed, they are used in a generic and descriptive sense and not for purposes of limitation, the scope of the invention being set forth in the following claims.

We claim:

1. A circular knitting machine having means to feed two yarns in a plating relation and to maintain plating control thereof, pattern means to alter during knitting the presentation of needles as desired to take lap threads, and means to present lap threads to such needles, whereby said lap threads are knitted onto the surface of the fabric.

55 2. A circular knitting machine having means to feed two yarns in a plating relation and to maintain plating control thereof, a pattern member, cam means controlled thereby and adapted by reason of such control to alter the presentation of needles of the circle of needles to take lap threads, and means to present lap threads to the presented needles.

3. A circular knitting machine having means to feed two yarns in a plating relation and to maintain plating control thereof, a

pattern member for selectively controlling among themselves the needles to take lap threads, jack cam means controlled by said pattern member, jacks for lap thread needles of the circle, and adapted to elevate the selectively controlled needles to take lap threads and means to feed lap threads to such needles.

4. A circular knitting machine having means to feed two yarns in a plating relation and to maintain plating control thereof, a pattern member for selectively controlling among themselves the needles to take lap threads, means to move the same to present fresh surfaces thereof, jack cams adapted to be moved into functioning relation by said pattern means, jacks having contrasting formations to be acted upon by said cam means, thereby to elevate predetermined needles selected by the pattern member among themselves to take lap threads, and means to feed lap threads to such needles.

5. A circular knitting machine having means to present two yarns to the needles in a plating relation and to maintain plating control thereof, pattern means to alter during circular knitting the presentation of needles as desired to take lap threads, and means to present lap threads to such needles, whereby said lap threads are knitted onto the surface of the fabric.

6. A circular knitting machine having means to present two yarns to the needles in a plating relation and to maintain plating control thereof, a pattern member to vary the number or identity of the needles to be presented to take lap threads, cam means controlled by said pattern member and adapted to cause the presentation of predetermined needles of the circle of needles to take lap threads, and means to present lap threads to presented needles.

7. A circular knitting machine having means to present two yarns to the needles in a plating relation and to maintain plating control thereof, a pattern member, to alter during circular knitting, among themselves, the presentation of needles to take lap threads, jack cam means controlled by said pattern member, jacks for desired needles of the circle and adapted to elevate desired needles to take lap threads, and means to feed lap threads to such presented needles.

8. A circular knitting machine having means to present two yarns to the needles in a plating relation and to maintain plating control thereof, means to feed lap threads to desired needles, and means acting during circular knitting predeterminedly to alter the presentation of needles to receive the lap threads whereby the actual needles that are presented to take the lap threads are varied among themselves.

9. A circular knitting machine having means to present two yarns to the needles

- in a plating relation and to maintain plating control thereof, means to feed lap threads to predetermined selected needles, and means to vary during circular knitting as desired the period during which said needles continue to take the lap threads and to select during circular knitting the needles that are to take the lap threads whereby varying lap pattern arrangements may be provided.
10. A circular knitting machine having means to feed two yarns in a plating relation and to maintain plating control thereof, means to feed lap threads to predeterminedly selected needles, and means to cause during the knitting operation alternation in the presentation of the needles receiving the lap threads.
11. A circular knitting machine having means to feed two yarns in a plating relation and to maintain plating control thereof, means to feed lap threads to predeterminedly selected needles, and means acting during circular knitting to vary as desired the period during which said needles continue to take the lap threads, whereby lap pattern areas of varying length may be provided.
12. A circular knitting machine having means to feed two yarns in a plating relation to the needles, means to feed a plurality of lap threads so as respectively to form areas distinct from each other and means to cause predetermined needles of the circle of needles, not receiving one of said two plating yarns, to receive and knit the respective lap threads, and means to float the other of said two plating yarns at those areas where the lap threads are knitted with the first mentioned plating yarn.
13. A circular knitting machine having means to feed two yarns in a plating relation to the needles, means to feed a plurality of lap threads so as respectively to form areas distinct from each other and means to cause predetermined needles of the circle of needles, not receiving one of said two plating yarns, to receive and knit the respective lap threads and to permit each lap thread to float at the back of its said area, and means to float the other of said two plating yarns at a part at least of those areas where the lap threads are knitted with the first mentioned plating yarn.
14. A circular knitting machine having means to feed two yarns in a plating relation to the needles and to maintain plating control of one of said yarns while knitting lap threads onto the surface of the fabric, by floating one of said two plating yarns at those areas where the lap threads are knitted with the other of said plating yarns means to feed a plurality of lap threads so as respectively to form areas distinct from each other and means to cause predetermined needles of the circle of needles, not receiving
- one of said two plating yarns, to receive and knit the respective lap threads.
15. A circular knitting machine having means to feed two yarns in a plating relation to the needles, means to feed a plurality of lap threads so as respectively to form areas distinct from each other and means to cause predetermined needles of the circle of needles, not receiving one of said two plating yarns, to receive and knit the respective lap threads, and means to maintain plating control of said two plating yarns at those areas where the lap threads are knitted into the fabric, by floating one of said plating yarns at a part at least of said areas.
16. A circular knitting machine having means to feed two yarns in a plating relation to the needles, means to feed a plurality of lap threads so as respectively to form areas distinct from each other and means to cause predetermined needles of the circle of needles, not receiving one of said two plating yarns, to receive and knit the respective lap threads, and means to maintain plating control of said two plating yarns at those areas where the lap threads are knitted into the fabric, by floating one of said plating yarns throughout said areas.
17. That method of knitting a plated fabric having lap thread ornamentation on the outer surface thereof which consists in feeding two threads in a plating relation to the needles, introducing a plurality of lap threads so as respectively to form areas distinct from each other and to float each lap thread at the back of its own area and maintaining plating control upon both said two plating yarns by floating one of them at those areas whereat lap threads are knitted with the other of said plating yarns.
18. A circular knitting machine comprising means to feed two yarns in a plating relation to the needles and to maintain plating control thereof, means to feed a series of lap threads to selected needles, and means acting during the knitting operation to alter the presentation of needles that receive said lap threads, including a pattern drum having a series of circumferentially arranged sets of cams, jack cams adapted to be moved into action by said circumferentially arranged cams, and jacks in the needle grooves having contrasting formations for elevating predetermined needles to take the lap threads.
19. A circular knitting machine comprising means to feed two yarns in a plating relation to the needles and to maintain plating control thereof, means to feed a series of lap threads to selected needles, and means acting during the knitting operation to alter the presentation of needles that receive said lap threads, including a pattern drum having a plurality of circumferentially arranged cams, jack elevating and depressing cams controlled in action by the cams of said drum, and con-

trasting jacks adapted to be acted upon by said jack cams to cause the presentation of desired needles to the lap threads.

20. A circular knitting machine comprising in combination, a series of needles, means to introduce a main yarn or yarns thereto, a member having means to present a series of lap threads to separate selected sets of needles, said member being mounted upon a fixed axis parallel and eccentric to the axis of the needle circle, means to move said member upward along said axis sufficiently to clear the idle needles during heel and toe work, and means to move said member upward to a greater distance along said axis to permit transferring.

21. A circular knitting machine comprising in combination, a series of needles, means to introduce a main yarn or yarns thereto, a member having means to present a series of lap threads to separate selected sets of needles, said member being mounted upon a fixed axis parallel and eccentric to the axis of the needle circle, and means for automatically moving said member along said axis to different distances substantially as described.

22. A circular knitting machine comprising in combination a series of needles, means to introduce a main yarn or yarns thereto, a member having means to present a series of lap threads to separate selected sets of needles, said member being mounted upon a fixed axis parallel and eccentric to the axis of the needle circle, said member being secured in a readily detachable manner at the lower end of its support.

23. In a type of circular knitting machine adapted to introduce one or more lap threads each to a selected group of knitting needles of the machine in addition to the main yarn or yarns, yarn-engaging means located in substantial proximity to the needle circle to act upon a retiring main yarn or yarns, a substantially semi-circular plate-like member circumscribed by the needle circle, and having a crescent-shaped finger extending in parallelism with substantially a semi-circle of the needles, and along which the lap threads move in the knitting operation, and from the end of which finger they are released, substantially remote from the said yarn-engaging means.

24. In a type of circular knitting machine adapted to introduce one or more lap threads each to a selected group of knitting needles of the machine in addition to the main yarn or yarns, yarn-engaging means located in substantial proximity to the needle circle to act upon a retiring main yarn or yarns, a substantially semi-circular plate-like member circumscribed by the needle circle, and having a crescent shaped finger extending in parallelism with substantially a semi-circle of the needles, and along which the lap threads move in the knitting operation, and from the end of which finger they are re-

leased and pass beneath the said plate-like member below the plane of the said yarn engaging means.

25. In a type of circular knitting machine adapted to introduce one or more laps threads each to a selected group of knitting needles of the machine in addition to the main yarn or yarns, yarn-engaging means located in substantial proximity to the needle circle to act upon a retiring main yarn or yarns, a plate-like member within the needle circle cut away to provide a substantially semi-circular crescent shaped guiding or receiving finger for the lap threads along which the same slide to be released at the end thereof substantially remote from the said yarn-engaging means.

26. A circular knitting machine having means to feed two yarns in a plating relation to the needles, means to cause predetermined needles of the circle of needles to receive lap threads and to knit the same upon needles receiving and knitting one only of the said two plating yarns, means to float the other of said two plating yarns at those areas where the lap threads are knitted with the first mentioned plating yarn, and means to cause variation in the needles receiving lap threads.

27. A circular knitting machine having means to feed two yarns in a plating relation to the needles, means to cause predetermined needles of the circle of needles to receive lap threads and to knit the same upon needles receiving and knitting one only of the said two plating yarns, means to float the other of said two plating yarns at a part at least of those areas where the lap threads are knitted with the first mentioned plating yarn, and means to cause variation in the needles receiving lap threads.

28. A circular knitting machine having means to feed two yarns in a plating relation to the needles and to maintain plating control of one of said yarns while knitting lap threads onto the surface of the fabric, by floating one of said two plating yarns at those areas where the lap threads are knitted with the other of said plating yarns, and means to cause variation in the needles receiving lap threads.

29. A circular knitting machine having means to feed two yarns in a plating relation to the needles, means to feed lap threads to desired needles, means to maintain plating control of said two plating yarns at those areas where the lap threads are knitted into the fabric, by floating one of said plating yarns at a part at least of said areas, and means to cause variation in the needles receiving lap threads.

30. A circular knitting machine having means to feed two yarns in a plating relation to the needles, means to feed lap threads to desired needles, means to maintain plating

control of said two plating yarns at those areas where the lap threads are knitted into the fabric, by floating one of said plating yarns throughout said areas, and means to cause variation in the needles receiving lap threads.

31. That method of knitting a plated fabric having lap thread ornamentation on the outer surface thereof which consists in feeding two threads in a plating relation to the needles, introducing lap threads to desired needles, maintaining plating control upon both said two plating yarns by floating one of them at those areas whereat lap threads are knitted with the other of said plating yarns, and varying the needles receiving lap threads.

32. A circular knitting machine having means to feed two yarns in a plating relation and to maintain plating control thereof, means to feed a plurality of lap threads so as respectively to form areas distinct from each other, means to cause needles to take said respective lap threads and to knit said lap threads onto the outer surface of the fabric, and means automatically to vary the identity of the needles that take the respective lap threads, whereby the said areas are varied to produce pattern effects therein by such varying of the needles.

33. In testimony whereof, we have signed our names to this specification.

JOHN LAWSON.
ROBERT H. LAWSON.
